ABRADING MACHINE

Frederick A. Shultz, Franklin L. Speckman, Loren D. Woolley, Elwood T. Mahlmeister, and Leon N. Barnum, Dayton, Ohio, assignors to The National Cash Register Company, Dayton, Ohio, a corporation of Maryland

Application June 30, 1943, Serial No. 492,814

19 Claims. (Cl. 51—101)

This invention relates to abrading machines, and particularly to one capable of grinding an object to a very high degree of accuracy, and includes abrading machines to grind three dimensional objects of various formations to a very high degree of exactitude.

More specifically, the invention includes novel means to produce a three-dimensional control cam from a master or model cam.

Formerly the cams were finished by hand-lapping, which required a considerable amount of time and labor.

It is, therefore, an object of this invention to produce a machine or apparatus to grind objects or cams, and particularly such objects having a three-dimensional control surface.

Another object is to produce an apparatus to perform a grinding operation on the above mentioned types of objects or cams with such speed as to reduce the time and labor to a minimum, and at the same time maintain an extremely high degree of accuracy.

Another object is to produce an apparatus to grind a three-dimensional control cam in approximately twenty-five percent of the time formerly required by the hand method, while maintaining ultra-precision relative to all three dimensions of the cam.

A further object is the production of an ultra-precision device to control the work spindle and the master model.

Another object is to produce a novel adjustable control device to accurately determine all positions of the work, relative to all dimensions thereof, in relationship to the abrading or grinding means.

A still further object is the provision of a control device having the same radial dimension as the grinding wheel and means to change the radial dimension of the control device in order to keep it of the same dimension as the grinding wheel after the latter has been dressed, which decreases its diameter.

With these and incidental objects in view, the invention includes certain novel features of construction and combinations of parts, the essential elements of which are set forth in appended claims, and a preferred form or embodiment of which is hereinafter described with reference to the drawings which accompany and form a part of this specification.

In said drawings:

Fig. 1 is a plan view, in reduced scale, of the apparatus for grinding three dimensional cams and shows the work spindle carrying the master

and the piece to be worked upon, the slide and traveling table therefor, the driving means for the work spindle and the sliding table, which driving means is operated by an electric motor, the grinding wheel and electric driving motor for the same, the dressing device for the grinding wheel, and the master gage for gaging the distance between the control device which cooperates with the master cam and the grinding wheel.

Fig. 2 is a front elevation of a portion of the grinding apparatus and shows the work spindle carrying the master cam and the work to be operated upon, and the slide and traveling table, by means of which the work spindle may be moved in any position relative to the control device, as determined by the master cam.

Fig. 3 shows the master gage setting in position on the spindle slide to gage the distance between the control device and the grinding wheel.

Fig. 4 is a plan view partially broken away, showing the system of reduction pulleys and reduction gears which control the rotation and lateral movement of the work spindle.

Fig. 5 is a front elevation of the novel control device for the master cam.

Fig. 6 is a side elevation of the same.

Fig. 7 is an enlarged detail partly in section, showing how the specific part of the control device which cooperates with the master cam can be adjusted to change its radius to make it conform to the grinding wheel after the latter has been dressed down, thus reducing its diameter.

Fig. 8 shows a still further enlarged section of the control rod for the master cam and its mounting, and the clamp for retaining it in a definitely set position.

Fig. 9 is a side elevation showing a portion of the grinding wheel and the dressing means therefor.

Fig. 10 is a plan view of the dressing device for the grinding wheel.

Fig. 11 is an enlarged fragmentary view of the means for gaging the dressing means for the grinding wheel.

Fig. 12 is a side elevation of a portion of the dressing device and the gaging means therefor.

Fig. 13 is an enlarged plan view of one of the control bars which support the control rod for the master cam.

Fig. 14 is an end view of the same, looking toward the stem or cam end.

Fig. 15 is an end view of the same looking toward the V-bearing end.

Fig. 16 is a side elevation of the same.

Fig. 17 shows a modified form of clamping de-

vice for clamping the control rod on its V-bar bearings.

Fig. 18 shows a side view of one form of a three-dimensional cam, which is ground by the present invention.

Fig. 19 is an end view of the same.

Fig. 20 is a side elevation showing a portion of the grinding wheel and the work spindle with the work thereon in cooperation with the grinding wheel, and also illustrates a portion of the traveling table and slide which supports the work spindle.

Fig. 21 is a side elevation of another form of a three-dimensional cam ground by the present invention.

Fig. 22 is an end view of the same.

Fig. 23 is a third form of a three-dimensional cam which is ground by the present invention.

Fig. 24 is an end elevation of the same.

GENERAL DESCRIPTION

Described in general terms, the invention includes novel means to produce an extremely accurate three-dimensional object, such as a cam, from a master or model, with a great saving in time as compared with the former hand method of production.

To accomplish the above, a novel abrading apparatus has been constructed. This apparatus includes several machine elements all mounted on a common base and all cooperating to produce the desired result in the most economic and efficient manner.

The work spindle carries a master or model adjacent one end thereof, and the work to be finished, by grinding, adjacent the other end thereof. The spindle is driven at a very slow speed by an electric motor through a system of reduction gears and pulleys.

The work spindle is carried by a reciprocating slide which is mounted on a reciprocating traveling table, which in turn is mounted on the base of the apparatus. The sidewise travel of the table is accomplished by an electric motor and a system of reduction gears and pulleys above mentioned, with the addition of a further gear reduction system driven thereby. Thus the table is moved sidewise to carry the master past a novel adjustable control device and to carry the work past an abrading or grinding means.

The slide upon which the work spindle is directly mounted is moved toward the rear by a weight attached thereto, in order to hold the master in constant contact with the control device at all times, while the master is being rotated and moved sidewise relative to the control device, whereupon the work is always held in the same position relative to the grinding means that the master holds relatively to the control device, whereby said work is accurately ground to the exact size and shape of the master, thus producing an extremely accurate counterpart.

The abrading or grinding means is in the form of a wheel, the grinding edge of which is of the same contour as the contour of the control device. The grinding wheel is driven by a separate motor mounted on the base.

The control device is mounted on a table adjustable sidewise and forward and rearward on a bed secured to the base. This control device is cylindrical and is bent to form a true arc, and is also adjustable independently of its table to maintain a true concentricity of its control or contact surface so that it can be adjusted around the center of its accurate contour to periodically pre-

sent new points of control to the master, thus insuring accurate duplications of the master at all times.

The control rod is mounted on a plurality of 5 V-blocks carried on rods projecting radially from the center of the arc of the control device or rod, and bearing on an adjustable control cone. The V-surfaces of the V-blocks are cut on a radius from the center of said arc, and when the control 10 rod is clamped in the accurately cut V-block, its concentricity is definitely assured.

The sidewise adjustment of the control table is for maintaining a constant lateral distance between the control rod and the grinding wheel.

15 A master feeler gage set according to a master block and pin arrangement is provided to check these distances between the control rod and the grinding wheel.

To keep the contour of the grinding wheel in 20 true condition at all times, a dressing device is adjustably mounted on a bed on the base, directly back of the grinding wheel.

As the grinding wheel is decreased in diameter, 25 due to the dressing down of the same to keep it in accurate formation, the adjustable cone of the control device is operated or adjusted so that the working or outside radius of the control rod may at all times be held the same radius as the radius of the grinding wheel, to insure that the 30 object being ground, in the present instance a three-dimensional cam, will be the exact duplicate of the master, which cooperates with the control rod to bring the cam to be ground into proper relationship with the grinding wheel.

DETAILED DESCRIPTION

Work spindle and rotary drive therefor

A work spindle 60 (Figs. 1, 2 and 20) is journaled by means of ball bearings 61 mounted in bearing heads 62 and 63 of a slide 64, to be later described in detail. Retaining caps 65, 66, 67 and 68 keep the bearings in position in the heads 62 and 63. A portion of the spindle 60 is threaded and has two lock nuts 70 adjacent the cap 67. A clamping collar 71 provided with a hub 73 is clamped on a shoulder 72 of the spindle, adjacent the cap 68. The lock nuts 70 and the clamping collar 71 are adjusted and locked into position to prevent end play of the spindle 60, thus retaining said spindle 60 in proper lateral position at all times.

The shoulder 72, of the spindle 60, carries a locating pin 74, which projects into a hole 75 (Figs. 18 and 19) of a three-dimensional cam 76, which in the present application is the object to be ground to duplicate, in exact contour, a master or model cam 77 (Figs. 1, 2 and 7) carried adjacent the left end of the spindle 60. This pin 74 insures that the cam 76 is in the proper angular location on the spindle prior to the grinding thereof.

The cam 76 is held in lateral position on the spindle between the hub 73 and a collar 78 by a lock nut 79 screwed on the end of the spindle 60.

65 The master cam 77 is held adjacent a shoulder 80 (Figs. 2 and 7) of the spindle 60 by an eccentric collar 81, which in turn is firmly held against the master cam 77 by a lock nut 82 screwed on the left end of the spindle 60. The collar 81 has a pair of internal tenons 83 (only one shown), which engage splines 84 in the spindle 60 whereby a locating pin 85 on the collar 81 projects into a hole 86 in the master cam 77, thus insuring proper angular location of the cam 77 on the spindle 60. 70 This locating pin 85 has the same angular loca-

tion relative to the splines 84 at all times, and therefore the clamping collar 71 can be easily and readily adjusted so that its locating pin 74 is in the same angular location prior to placing the cam 76 on the spindle.

The spindle 60 is rotated at a very low speed, approximately 15 R. P. M., so that in combination with the lateral travel of the spindle, to be later described, the three-dimensional cam 76 can be ground to a smooth surface, thus producing an extremely accurate duplicate of the master cam 77.

The rotary drive for the spindle 60 is from a motor 100 (Fig. 1) secured to a base 101, through a system of reduction pulleys and gears. This motor is rated at 1725 R. P. M. The armature shaft of the motor 100 carries a cone pulley 102, driving a belt 103, which drives another cone pulley 104 (Fig. 4) secured to a shaft 105 mounted in a gear box 106 (Figs. 1 and 4) secured to the base 101.

The shaft 105 carries a worm 107 driving a worm gear 108 secured to a shaft 109, which also has secured thereto a worm 110 driving a worm gear 111 secured to a shaft 112. A universal joint 113 connects the shaft 112 to a shaft 114, which is connected to a coupling sleeve 115 having slots 116 (only one shown) to receive a key 117 secured to and projecting from opposite sides of a shaft 118. A sleeve 119 covers the slots 116 and key 117 to prevent any foreign matter from interfering with the free sliding movement of the key 117 and shaft 118. Another universal joint 120 (Figs. 1 and 2) connects the shaft 118 to a shaft 121 journaled in a bearing hub 122 integral with the head 63. A double pulley 123 is secured to the shaft 121 and through belts 124 drives a double pulley 125 secured to the spindle 60. The slot 116 in the shaft 118 is to permit lateral or sidewise reciprocation of the table which carries the spindle slide 64, which table will be later described, and which is for the purpose of moving the master cam 77 past an adjustable arcuate control rod 130, to be later described, and at the same time move the cam 76 past a grinding wheel 131. The universal joints 113 and 120 permit the forward and backward movement of the slide 64, which carries the spindle 60 in order to maintain the master cam 77 in constant contact with the control rod 130, while at the same time properly presenting the cam 76 to the grinding wheel 131 to be ground according to the shape of the master cam 77.

From the above description it will be clearly seen that the driving power from the motor 100 (Fig. 1), through the system of shafts, reducing gears and pulleys, just described, rotates the spindle 60 at a slow speed to turn the master cam 77 and the cam 76 while the master cam is held in contact with the adjustable arcuate control rod 130 to control the position of the cam 76 relative to the abrading or grinding wheel 131.

The grinding wheel 131 is secured to a shaft 132 mounted in a bearing bracket 133 secured to the base 101. A belt 134 driven by a motor 135, mounted on the base 101, drives the shaft 132 and the grinding wheel 131 at the proper predetermined speed.

Spindle slide

The previously mentioned spindle slide 64 is mounted to have free movement from front to rear, and rear to front, to maintain the master cam 77 in constant contact with the control rod 130, which simultaneously presents the cam 76

to the grinding wheel 131 for finished grinding to duplicate the master cam 77.

Secured to the slide 64 (Fig. 2) so as to be flush with the bottom thereof, are three V-bars 140, 141 and 142. The V-bar 140 is in the center and at the front of the slide 64, and the V-bars 141 and 142 are located at the rear and along the side edges of the slide 64. These V-bars 140, 141 and 142 ride on sets of balls 143, which in turn ride in V-bars 144, 145 and 146, secured to a traveling table 147 so as to be flush with the top thereof. Shields 148 secured to the table 147 enter grooves in the slide 64 to prevent any foreign bodies, such as dirt and emery from getting into the bearings of the slide 64 as the same is moved back and forth.

A weight 149 (Fig. 1) below the base 101, is fastened to a cable 150, which runs over a pulley 151 and is connected to the slide 64 to hold the master cam 77 in contact with the control rod 130 while the spindle 60 is rotating, thus presenting the cam 76 to the grinding wheel 131, to be ground the exact shape of the master cam 77. As the contour of the master varies on any of its radii, the slide 64 rides freely on the sets of balls 143 forward and backward, as determined by the master cam. As these movements forwardly and backwardly of the slides 64 take place, the master cam 77 is moved laterally the entire length of the same by the traveling table 147 in a manner and by means to be later described.

When the grinding operation on the cam 76 has been completed by the wheel 131, the operator grasps a handle 154 and draws the slide 64 forwardly, as viewed in Figs. 1 and 2, to the left as viewed in Fig. 20, to remove the spindle 60 far enough away from the grinding wheel 131 so that the operator can easily remove the finished cam 76 and place another unfinished cam on the spindle 60 to be ground.

Since the slide 64 is drawn to the rear, to the right as viewed in Fig. 20, by the weight 149, should the operator's hand slip off the handle 154 the wheel 131 might be damaged by the cam 76 or the spindle 60 striking against the wheel, or if the cam 76 was still on the spindle it would undoubtedly damage the cam to such an extent that it could not pass inspection. The master cam 77 would also strike the control rod 130 and probably damage them.

To prevent such contact by the cam 76 or spindle 60 with the wheel 131 in an accidental manner, a safety device is provided which will now be described.

Journalized in the slide 64 (Figs. 2 and 20) is a shaft 155 having secured to the outer or front end thereof a knurled knob 156 for hand manipulation of the shaft 155. Secured near the inner end of the shaft 155 is an arm 157, the free end of which is held by a torsion spring 158 against the top of a lug 159 on an adjustable safety slide 160 mounted in the traveling table 147. This slide 160 is provided with a notch 161 and the front end of the slide is cut away to form a shoulder 162.

If the operator, in removing the slide 64 so as to remove the cam 76 from the wheel 131, merely takes hold of the handle 154 and draws the slide 64 to the left as viewed in Fig. 20, as soon as the end of the arm 157 passes off the lug 159 the spring 158 will rock the arm 157 and shaft 155 counter-clockwise, as viewed in Fig. 2, whereupon the free end of the arm 157 will drop in the notch 161 so that if the operator's hand should slip off the handle 154 at this time, the arm 157 would stop against the left-

hand side of the lug 159, and thus prevent the cam 76 from coming into contact with the wheel 131. As the operator continues to draw the slide 64 to the left, as viewed in Fig. 20, the lefthand angled surface of the notch 161 will automatically turn the arm 157 in a clockwise direction against the tension of the spring 158, and as the free end of the arm 157 passes the shoulder 162 of the slide 160, the spring 158 will again rock the arm 157 counter-clockwise, moving the free end of said arm down in front of the shoulder 162, thus locking the slide 64 in its inoperative position, in which position the operator usually places the slide when changing cams on the spindle 60.

This safety slide 160 is adjustable in order to take care of various sized cams or other objects which are to be placed upon the spindle 60 for grinding. This adjustment of the slide 160 is brought about by a screw 163, which is threaded into the slide 160 and has a knurled knob 164 on the end thereof for hand manipulation. A collar 165 is pinned to the screw 163 so that when the knurled knob 164 is turned, the slide 160 may be moved in and out to any desired extent, depending of course upon the length of the threaded section of the screw 163.

Traveling table and operating means therefor

The traveling table 147, which has been previously mentioned, for carrying the master cam 77 sidewise past the control rod 130 and of course for simultaneously carrying the cam 76 to be ground, past the grinding wheel 131, will now be described.

The sliding table 147 is best shown in detail in Figs. 2 and 20. Secured to the table 147 so as to be flush with the bottom thereof, are three V-bars 170, 171 and 172. The V-bar 170 is in the center and at the right (Fig. 4), and the V-bars 171 and 172 are located at the left end of the table along the front and rear sides thereof. These V-bars 170, 171 and 172 slide on sets of balls 173, which in turn work in a bearing plate 174, rigidly secured to the base 101. This bearing plate has V-notches 175, 176 and 177, which are located opposite the V-bars 170, 171 and 172, respectively. Shields 178 secured in the bearing block 174 enter grooves in the table 147 to prevent any dirt or emery from getting into the bearings of the table 147 as it is being moved sidewise.

To prevent the table 147 from rising or jumping up or bumping as it is traveling sidewise in either direction, there is provided a pair of roller bearings 180 (Figs. 1, 2 and 20) which are mounted on tenons of a block 182, slidably mounted on a vertical stud 183, which is screwed into the base 101. This stud 183 projects up through an opening 184 of the table 147 and the pair of rollers 180 roll on a finished surface 185 of a boss on the top of the table 147. The pair of rollers 180 are held in proper position by spacing washers 186, which in turn are held by a pair of lock nuts 187 screwed on the end of the stud 183.

The left end of the table 147, as viewed in Fig. 2, has secured thereto a bracket 190 carrying a roller 191 cooperating with the race 192 of a drum cam 193 secured to a shaft 194, mounted in parallel vertical arms 195 of a block 196, which is secured to the base 101.

As viewed in Figs. 1 and 2, the roller occupies the righthand portion of the race 192, and therefore as the drum cam 193 is turned in a clockwise direction the table 147 is moved to the left

to move the master cam 77 past the control rod 130 and at the same time move the cam 76 to be ground past the grinding wheel 131.

So that there will be no back-lash or lost motion or bobbing from side to side of the table 147, due to working clearances between the roller 191 and the cam race 192, a weight 197 connected to a cable 198, which runs over a pulley 199, holds the roller 191 against the righthand side wall of the race 192 as the drum cam 193 is rotated. This cam race 192 is cut so that a one-half revolution of the drum cam 193 moves the table 147 from the position shown in Fig. 2 toward the left a distance sufficient to move the master cam 77 past the control rod 130, and at the same time move the cam 76 to be ground past the grinding wheel 131. As the drum cam 193 completes its rotation, the cam race 192, as will be clear from the view of this race in Fig. 2, will move the table 147 back to the right as viewed in Fig. 2, to move the master cam 77 and the cam 76 to be ground past the control rod 130 and wheel 131 from left to right, as viewed in Fig. 1.

In other words, a half-turn of the cam 193 is sufficient to complete the grinding of one of the cams 76, after which the spindle 60 is stopped from rotating and the slide 64 is drawn forwardly and the finished cam 76 removed and another unground cam placed on the spindle 60, whereupon the slide 64 is again moved into position and the table 147 moved to the right to grind a second cam.

The means for rotating the shaft 194 to operate the drum cam 193, as above described, will now be considered.

Since the spindle 60 is driven at a very slow speed, 15 R. P. M., as above mentioned, it is necessary to move the traveling table 147 at an extremely slow speed in order to get a good, clean and accurate grinding job on the cam 76.

Therefore, in order to move the traveling table 147 at the extremely slow speed that is necessary, it is necessary to rotate the drum cam 193 at a very slow speed.

This rotation of the cam 193 is accomplished from the previously described shaft 112, which, it will be remembered, is operated to drive the spindle 60 at about 15 R. P. M.

Secured to the shaft 112 (Fig. 4) is a worm 200 which drives a worm gear 201 fastened to a shaft 202, which in turn carries a worm 203 which drives a worm gear 204, which is secured to a shaft 205 journaled in the gear box 106.

The ratio of the gear drive from the shaft 105, which carries the cone pulley 104, which it will be remembered is driven from the motor 100, to the shaft 205, is approximately 20,000 to 1 reduction, and consequently the shaft 205 is driven at approximately .038 R. P. M.

A flexible coupling 206 is connected to the shaft 205 by means of a pilot screw 207, which extends into a groove 208 in the shaft 205. This flexible coupling 206 is also connected by means of a key 209 to a shaft 210. Secured on the end of the shaft 210 is a hubbed collar 211. The periphery of the collar 211 is threaded to receive a coupler 212 which is slipped over the hub of a disk 213 secured to the shaft 194. The collar 211 may be made of steel and the disk 213 may be made of bronze or any other suitable metal.

When the coupler 212 is screwed tightly on the threaded collar 211, the faces of the collar 211 and disk 213 are drawn tightly together, and thus the rotation of the shaft 210 is transmitted

to the shaft 194, to which the drum cam 193 is secured.

From the above description it can be seen that the shaft 194, through the system of reduction gears and pulleys, is driven at an extremely slow speed by the motor 100.

As previously pointed out, a one-half rotation of the shaft 194 and drum cam 193 is sufficient to carry the master cam 77 past the control rod 130 and to carry the cam 76 to be ground past the grinding wheel 131.

At the end of the grinding of one of the cams 76 the slide 64 is moved forwardly as previously described, and of course the motor 100 is stopped by the usual switch button, not shown. The finished cam 76 is removed from the spindle 60 and an unfinished cam is placed thereon, ready for grinding.

Should the shaft 194 and cam 193 have rotated slightly past the 180 degree position, then in order to start the sliding table 147 at the proper place, the operator merely grasps the coupler 212 and loosens the same, thus releasing the disk 213 from the driving collar 211, and then manually turns the shaft 194 and drum cam 193 by means of a knurled collar 214, which is pinned to the shaft 194 for this purpose. After the shaft 194 has been so adjusted to bring the spindle 60 to the proper starting place, the operator again tightens the coupler 212 on the driving collar 211 so that the disk 213 and shaft 194 will be driven from the motor 100.

From the above description it can be clearly seen that as the spindle 60 is being rotated very slowly to turn the master cam 77 against the control rod 130, and at the same time turn the cam 76 to be ground, the shaft 194, and drum cam 193 are rotated still much slower than is the spindle 60, with the consequent result that the table 147 is moved very slowly sidewise to move the master cam 77 sidewise relatively to the control rod 130.

Therefore, since the master cam 77 is a three-dimensional cam, as it is being rotated and at the same time moved laterally relatively to the control rod 130, all points of the surface of this master cam come in contact with the control rod 130, and consequently the cam 76 is ground by the grinding wheel 131 in exact duplicate with the master cam 77.

Control device

As has been previously stated in a general way, the control rod 130 is of a diameter comparable to the thickness of the grinding wheel 131. This wheel 131 is dressed so that the grinding face thereof, is a true semi-circle corresponding to the control rod 130. Moreover the control rod 130 is adjustably mounted so that its outside periphery or the curvature of that surface of the control rod 130 with which the master cam 77 comes into contact, may be kept at all times the same radius as the grinding surface of the grinding wheel 131.

With this type of construction it can be seen that as the grinding wheel 131 is dressed down, which is necessary with all grinding wheels, and particularly when attempting to produce such an exact duplicate as the invention here produces, it is necessary to dress the grinding wheel much more often than it is with the ordinary plain surface grinding.

Therefore, as this wheel 131 is dressed down it gradually becomes of smaller diameter, and in order to compensate for this dressing of the

wheel 131 the control rod 130 is uniquely mounted and is adjustable so that it can at all times be kept of the same radius as the radius of the grinding wheel 131.

- 5 The control device carrying the control rod 130 includes a base 220 (Figs. 1, 5 and 6) adjustable from front to back to take up any discrepancies in the machining of parts or any backlash that might occur through wear and from other causes, and also a head which is adjustable relatively to the base 220 for the purpose of maintaining an accurate dimension of distance between the center of the control rod 130 and the center of the grinding wheel 131 so that the cam 15 76 will be ground exactly the same at all points along its length as the master relatively to the variable radial distances on this length. As has been described above, the master cam 77 and the cam 76 to be ground are always located exactly 20 the same distance apart, and it is this same distance that must positively be maintained between the rod 130 and the grinding wheel 131.
- The control device is best shown in Figs. 5 to 8 in detail and in Fig. 1 generally. It might be well to state here that the center line of the rod 300, carried by the head 221, which center line is the axis of the control rod 130, should coincide with, or be on the same horizontal line, as the axis of the grinding wheel 131.
- 30 The base 220 is mounted to slide on a dovetailed block 222 integral with the base 101. The base 220 carries a gib 223, adjustably by gib screws 224 for determining the tightness of the sliding fit desired between the base 220 and the 35 dovetailed block 222. A locking or set screw 225 is provided and is threaded into the gib so that the base 220 may be securely locked after it has been once adjusted to the proper position.

- The head 221 has a dovetailed slide connection 40 indicated at 226 (Fig. 6) with the base 220 and a gib 227 is adjusted by means of gib screws 228 to arrive at the proper sliding fit for the dovetailed connection 226. A locking or set screw 229 is used to lock the head 221 after it has been 45 adjusted into the desired position.

- The base 220, and consequently the head 221 may be adjusted from front to back as viewed in Fig. 1, for the purposes of taking up any lost motions or due to backlash or machining of the 50 parts so that the control rod 130 will be in the proper position relative to the surface of the grinding wheel 131. This is accomplished by the following means:

- Threaded into the front of the base 220 is a rod 55 230 having a bearing in a bracket 231 secured to the base 101, as shown in Fig. 1. A spoked wheel 232 is secured to the outer end of the rod 230. The wheel 232 and a collar 233 pinned to the rod 230 adjacent the bracket 231 prevent any longitudinal movement of the rod 230 while it is being turned either clockwise or counter-clockwise by the spoked wheel 232. Slipped over the wheel 232 is a graduated collar 235 held in position by a pair of thumb screws 234 (only one shown). The 60 graduations on the collar 235 cooperate with a fixed line 236 on the bracket 231 so that when the wheel and rod are turned, the number of graduations on the collar 235 will tell how many thousandths of an inch the rod 230 has been moved either forward or backward, and consequently 65 how far the base 220 has been moved to make any necessary fine adjustments.

- It can be seen that with this micrometer adjustment of the rod 230 any lost motion or backlash due to the manufacture of the parts can

be taken out so as to properly position the control rod 130 relative to the grinding wheel 131.

Before such adjustment of the table 220 can take place, it is of course necessary to loosen the locking screw 225, after which it can be tightened again to maintain the definite set position between the base 101 and the base 220 of the adjustable control device.

As has been previously stated, it is absolutely necessary that the distance from the rod 130 to the grinding wheel 131 be maintained at all times. Should this distance vary or become changed, then the head 221 may be adjusted sidewise by a screw 240 threaded into the head 221. This screw has a bearing in a bracket 241, which is integral with the control device base 220, and the screw 240 is prevented from any longitudinal movement in the bracket 241 by means of a pair of collars 242 which are pinned to the screw 240. A hand knob 243 is secured to the outer end of the screw 240 so that the screw may be turned.

Before turning the screw it is, of course, necessary to release the locking screw 229 (Figs. 1 and 6) so that the head 221 may be freely moved relatively to the base 220. It can be clearly seen that by turning the knob 243, the head 221 may be shifted either to the right or to the left (as viewed in Figs. 1 and 5), for the purpose of accurately setting the rod 130 the proper distance away from the grinding wheel 131.

This distance between the control rod 130 and the grinding wheel 131 is checked by a dial gage 244, shown in Figs. 1 and 3. This dial gage is normally kept on a block 245 carrying fixed pins 246 and 247, which have been located the exact distance that the rod 130 is to be maintained from the grinding wheel 131. The diameter of these pins 246 and 247 is of the same diameter as the rod 130 and the thickness of the grinding wheel 131.

A rigid V-block 248 of the gage 244 contacts the pin 246 and a pivoted V-block 249 contacts the pin 247. The V-block 249 cooperates with a sliding pin 250, which operates a hand 251 on a reading dial 252, which is a part of the gage 244.

The dial 252 is set so that the hand 251 reads zero before the gage 244 is removed from the block 245 and pins 246 and 247. After the dial 252 has been set so that the hand reads at zero, the gage 244 is then rested upon a pair of projecting fingers 253, which project from the slide 64, with the rigid end or V-block 248 of the gage 244 in contact with the grinding wheel 131. The pivoted V-block 249 is then placed against the rod 130 (as shown in Fig. 3), and if the hand 251 now reads zero, then the rod 130 is the exact proper distance from the wheel 131. If there is a variation so that the hand 251 shows that the distance is not the same as that set by the master pins 246 and 247, then the hand wheel 243 (Fig. 5) is turned to move the head 221 either to the right or to the left as viewed in Figs. 1 and 5, until the hand 251 registers zero on the reading dial 252, at which time the rod 130 will be the proper distance away from the grinding wheel 131.

As has been previously stated, this is a very important dimension to maintain because particularly of the three-dimensional cams which are being ground by the wheel 131. It is, therefore, absolutely necessary that the cam 76 be started to be ground at the exact proper corresponding part on the master cam 77 which can be done only when the rod 130 is maintained the proper distance from the grinding wheel 131, because it

will be remembered that the master cam 77, and the cam 76 to be ground, are in a definite fixed relation to each other on the spindle 60.

The manner of mounting and adjusting the control rod 130 to change its control surface radius will now be described in detail. A sleeve 260 has a tenon 261 (Fig. 5) pressed into a counterbore in the righthand face of the head 221. This sleeve 260 also has a shoulder 262 which abuts against the face of the head 221 and is held securely against the same by means of fillister head screws 263. Journalled on the sleeve 260 are disks 264 and 265 between which is journalled a circular plate 266, having five radially drilled holes 267 for the reception of five stems 268 of five V-blocks 269, upon which the control rod 130 is adapted to be clamped to hold it in position for the master cam 77 to operate against to control the grinding of the cam 76. The V-notches are cut on an arc the center of which coincides with the center of the plate 266. Mounted opposite the V-blocks 269 and between the disks 264 and 265 by means of screws 270 is an arcuate spacing block 271.

By referring to Fig. 7, it will be noted that the disks 264 and 265 are relieved on their adjacent faces so that that part of the disks 264 and 265 which engages the V-blocks 269 is narrower than the relieved portion. Therefore, these two disks, 264 and 265, form clamps for the V-blocks 269 when the disks 264 and 265 are drawn up tightly against the shoulder 262 by means of a pair of lock nuts 272.

The inner ends of the stems 268 are tapered as shown in Figs. 13, 14 and 16, and have beveled ends 274 which contact a cone 275 (Figs. 5 and 7) the purpose of which will be hereinafter described. By referring particularly to Figs. 15 and 16, it will be noted that the V-blocks 269 are relieved as at 276, at right angles to the direction of the V cut in the end of the V block 269. This gives a better and more accurate bearing for the rod 130 when it is clamped in the V of the block 269.

The cone 275 forms a bearing for the beveled ends 274 of the stems 268 of the V-blocks 269. The control rod 130 is clamped in the V's of the V-blocks 269 by clamps 277 and 278. These clamps are each mounted on a eye bolt 279 held in position by a knurl-handled pin 280. These clamps 277 and 278 are of such a size as to have a slip fit between the outer circumferential sections of the disks 264 and 265. A link 281 is held between the disks 264 and 265 by a knurl-headed pin 282. This link 281 has a rounded end fitting in a groove 283 located near the end of the clamp 277. This link 281 forms a bearing so that when the clamp 277 is tightened down on the eye bolt 279 by a wing nut 284, the forward end of the clamp 277 which has a V cut therein to bear on the rod 130 will be drawn down tightly against this rod 130. The clamp 278 is clamped down on the lower portion of the rod 130 in exactly the same manner by a wing nut 284 on an eye bolt 279. A guiding pin 285 prevents the link 281 from falling down in between the disks 264 and 265 during the assembly and tightening up of the control rod 130.

From the above it will be clearly seen that the outer surface of the rod 130 will be bent to an absolutely true concentricity relative to the center of the head 221, the axis of which it will be recalled coincides with the axis of the grinding wheel 131.

Along the face marked 286 (Fig. 5) are a series

of graduations placed approximately four degrees and fifteen minutes apart. Secured to the top of the head 221 is an indicator pointer 287.

After a certain number of cams have been ground the position of the control rod 130 relative to the master cam can be easily changed so as to present a new surface of the control rod 130 to the master cam to make sure the cams being ground are exact duplicates of the master. The purpose of this, of course, is because of the wear on the control rod 130 occasioned by the constant contact with it by the master cam 77 as the latter is being rotated and slid along the rod 130.

In order to quickly and easily adjust the rod 130 so that a new position thereof will cooperate with the master cam 77, the operator need only to loosen the two lock nuts 272 and then by means of a handle 288 (Fig. 6) which may be inserted in a hole in the arcuate bar 271, turn the disks 264 and 265 and collar 266 on the sleeve 260 to present a new portion of the rod 130 to the master cam 77. Prior to making this adjustment of the rod it is best to loosen the clamps 277 and 278 slightly by turning the wing nuts 284, thus relieving the pressure of the stems 268 on the cone 275. After the rod 130 has been adjusted, the wing nuts 284 are again tightened to maintain the true concentricity of the rod 130 relative to the center of head 221. The sleeve 260 has a slot 289 (Fig. 7) long enough to allow clearance for the stems 268 upon the maximum adjustment of the rod 130. As shown in Fig. 6, the rod 130 extends a little way into the clamp 278 and a pin 290 prevents the rod from falling through the clamp and getting away from contact with the V-blocks 269.

It has been previously stated that, as the diameter of the grinding wheel 131 is decreased due to the dressing down of the same in order to keep it in proper shape, the rod 130 may be adjusted so that the radius of that part of the rod which contacts the master cam 77 will be the same as the radius of the grinding wheel 131. To accomplish this adjustment the cone 275 may be adjusted, that is, moved to the right as viewed in Fig. 5, and downwardly as viewed in Fig. 7, to present a smaller diameter of the section of the cone as bearing for the beveled ends 274 of the stems 268 of the V-blocks 269. It can be seen that as the cone 275 is moved downward, as viewed in Fig. 7, and with the rod 130 being clamped tightly against the V-blocks 269, the working surface of the rod 130 can be controlled as to its diameter; that is, the radius of the control or working surface of the rod, against which the master cam 77 is slid and turned, can be reduced to make it conform to the radius of the reduced size of the grinding wheel 131, thus at all times insuring that the cam 76 which is ground will be an exact duplicate of the master cam 77.

The manner of mounting the cone 275, and of adjusting the same to reduce the radius of the rod 130 to conform with the grinding wheel, will now be described.

A rod 300 is mounted to slide in the head 221. This rod carries a Woodruff key 301 which slides in a groove 302 in the head 221. The rod 300 has a tenon 303 upon which the cone 275 is mounted. The tenon 303, shown in Fig. 7, is not quite as long as the length of the cone 275, and therefore the small end of the cone can be tightly clamped against the shoulder of the rod 300 by a washer

304 and a nut 305 screwed on a smaller tenon of the rod 300 beyond the tenon 303.

The left end of the rod 300, as viewed in Fig. 5, has a threaded tenon 306 upon which is mounted a nut 307 having a tapered flange 308 with scale marks thereon. This nut 307 is mounted between the face of the head 221 and a pair of fingers 309 fastened to the head 221 by screws 316.

- 10 When it is desired to reduce the working radius of the rod 130, the nut 307 is turned on the tenon 306, and since the rod 300 cannot turn due to the Woodruff key 301, the rod and cone 275 may be moved to the right, as viewed in Fig. 5, to present a smaller section of its conical diameter to the beveled ends 274 of the stems 268 of the V-blocks 269, upon which the rod 130 is mounted. The distance, of course, which the cone 275 is moved to the right to reduce the diameter of the rod 130 depends upon how much has been dressed off the diameter of the grinding wheel 131.

After the cone 275 has been adjusted, the rod 300 is locked in position relative to the head 221 by means of pinch bushings 310 and 311 (Figs. 5 and 6). The bushing 310 is threaded to receive a screw 312 which has pinned to the top thereof a handle 313 for ease of operation and for being able to make the pinch bushings 310 and 311 clamp the rod 300 to prevent any movement thereof. The bushing 300 is cut away as at 314 and the bushing 311 is cut away as at 315 to conform to the shape of the rod 300. These bushings 310 and 311 are loosely slipped into holes bored vertically in the head 221, and when the screw 312 is turned by the handle 313 the surfaces 314 and 315 of the bushings 310 and 311 firmly press against the side of the rod 300 and prevent any longitudinal movement of the rod 300 relative to the head 221.

Modified form of clamp for control rod

In addition to the clamping device shown in Fig. 6 for the control rod 130, there is shown in Fig. 17 a simplified and modified form of a clamping device for holding the true concentricity of the control rod 130 at all times.

Referring particularly to Fig. 17, the simplified clamping device for the control rod 130 includes clamps 320 and 321, which are mounted between the disks 264 and 265. The forward fingers of the clamps 320 and 321 are provided with V-notches to contact the outer periphery of the rod 130 as shown. Pins 322 and 323 provide bearing surfaces for the clamps 320 and 321 adjacent the clamping ends of the same. These pins project through the disks 264 and 265 through slots 324 and 325 in the clamps 320 and 321. These pins 322 and 323 are flattened where they cooperate with the slots 324 and 325 in order to give better bearing surfaces for the clamps 320 and 321. The clamps 320 and 321 are both pivoted at their right ends, as viewed in Fig. 17, to a block 328. Threaded into the block 328 is a screw 329 having a bearing on its inner end in a block 330 located between the disks 264 and 265 by dowel pins 331, and fastened to the plate 266 (not shown in Fig. 17, but shown in Fig. 7) by screws 332. The screw 329 is grooved near its inner end and a pin 333 prevents the screw 329 from being drawn out of the block 330 when the clamps 320 and 321 are loosened.

From the above illustration in Fig. 17 and the description, it will be clear that when the screw

329 is tightened or turned clockwise, the block 328 will be moved to the right and consequently, due to the pivotal connections of the pins 326 and 327 and the sliding and pivotal connections of the pins 322 and 323, the fingers of the clamps will be drawn very tightly against the control rod 130, causing it to firmly rest in the V-notches of all of the V-blocks 269.

When changing the position of the rod 130 relative to the master cam 71 for the purposes previously described, that is, to maintain greater accuracy in the grinding of the cams 76, the screw 329 is loosened slightly to relieve the pressure of the clamping fingers on the rod 130, which consequently relieves the pressure of the stems 268 (Fig. 7) of the V-blocks 269 against the cone 275. After this release of the clamps 320 and 321 a wrench 334, shown in dot and dash lines in Fig. 17, having two pins projecting into holes 335 in the disk 264 is used to rotate the disks 264 and 265, and consequently the control rod 130 to bring a new portion thereof adjacent the control cam 71. A pin 336 is provided in the clamp 321 to prevent the rod 130 from sliding through the clamp when the clamps are released for the purpose of adjusting the rod 130 into a new position.

As stated at the outset of this specification, the invention here is not limited to the grinding of a single type or form of three-dimensional cam. Another form of three-dimensional cam 337 is shown in Figs. 21 and 22. This cam is provided with a locating hole 338 comparable to the locating hole 75 in the cam 76.

In Figs. 23 and 24, a still different form of three-dimensional cam is shown, which can be readily ground by the machine embodying the present invention. This cam also has the locating hole 340, which is comparable to the locating hole 75 of the cam 76, which is shown in actual position on the work spindle 60.

Grinding wheel dresser

As has been previously stated, in order to grind the cam accurately so as to produce an exact duplicate of the master which is being used on the spindle 60, whether such master be the cam 76 (Figs. 18 and 19), 337 (Figs. 21 and 22), or the cam 339 (Figs. 23 and 24), or any other type of two- or three-dimensional cam, it is necessary to dress down the grinding wheel 131 in a very accurate manner so that the contour of this grinding wheel 131 will at all times be the same contour as the control rod 130, against which the master cam 71 works.

This dressing device is shown generally in Fig. 1, and in detail in Figs. 9 to 12, and includes a base 350 securely fastened to the machine base 101 directly to the rear of the grinding wheel 131. The base 350 is provided with a dovetailed block 351, upon which is adapted to slide a block 352, the same being adjusted and guided on the block 351 by the usual gib (not shown) which is fastened to the block 352 by gib screws 353.

In Fig. 9 the block 352 is shown in its extreme righthand position wherein a pin 354 is in contact with a stop pin 355 secured to the base 350. The block 352 may be locked in any position on the dovetailed block 351 by a locking screw 356.

The upper part of the block 352 is provided with a dovetailed way 357 for the reception of a slide 358. The adjustment of the slide 358 in the way 357 here again is accomplished by the usual gib (not shown) secured to the block 352 by gib screws 359. Handles 360 secured in the

side of the block 352 provide a convenient way for a quick adjustment of the blocks 352 from a non-dressing position into a position whereby the pin 354 is contacting the stop pin 355. After this adjustment has been made and the screw 356 operated to lock the block 352 relatively to the base 350, a screw 361 threaded into the block 352 and having a bearing in a block 362 secured to the slide 358 may be turned by a knob 363 secured to the screw 361 to adjust the slide 358 relatively to the block 352 from left to right, or right to left, as viewed in Fig. 9. The knob 363 is provided with graduations 364 which cooperate with a single line 365 on the block 362 so that a micrometer adjustment of the slide 358 may be made and the operator will know how far to turn the screw in order to dress off a certain number of thousandths of inches from the diameter of the grinding wheel 131. A collar 366 pinned to the screw 361 prevents any longitudinal movement of the screw 361 relative to the block 362, so that when the screw is turned the slide 358 will be adjusted relatively to the block 352. A locking screw 367 is provided to lock the slide 358 in the position into which it has been adjusted so that it cannot move after having once been set for a definite dressing operation of the wheel 131.

As has been previously stated, the contour of the grinding wheel 131 is semi-circular to correspond to the control rod 130. In other words, the radius of the periphery of the grinding wheel 131 is the same as one-half the diameter of the control rod 130.

Therefore, the dressing element, which in the present instance is a diamond point 370, is mounted for an arcuate movement of 180 degrees so as to dress the proper contour on the periphery of the grinding wheel 131.

Securely fastened to the top of the slide 358 is an arcuate-shaped T bar 371, upon which is mounted a block 372 carrying a rod 373 which supports the diamond point 370. The rear end of the rod 373 is threaded to receive a knurled collar 374. The block 372 may be swung 180 degrees on the T bar 371 by a handle 375 secured to the block 372. A locking clamp screw 376 is provided to lock the rod 373 in a fixed position relative to the block 372 after the diamond point 370 has been adjusted by moving the rod 373 by means of the knurled collar 374.

Prior to dressing the wheel a gage block 378 shown in dot and dash lines in Fig. 10, is set on the T bar 371 and held in a definite location by pins 377 which enter holes 378 (Fig. 1) in the top of the T bar 371. This gage block 378 has an opening to receive a bushing 379 (Fig. 12) which carries a gage pin 380, having four flattened sides so as to leave only short round surfaces 381 as shown in Fig. 11. This gage pin 380 may be turned by the operator grasping the bushing 379 and rotating the same to bring all four surfaces 381 into contact with the point of the diamond 370. This is done while the block 372 is at the same time being moved through 180 degrees of movement on the T bar 371 so as to make sure that the diamond is properly set to dress the wheel down at all points on the 180-degree surface, so that the periphery of the grinding wheel 131 will absolutely correspond to the periphery of the control rod 130. Stop pins 382 in the T bar 371 prevent the block 372 from being moved too far. Should the diamond point 370 not touch all four corners 381 of the gage pin 380, the rod 373 is adjusted by the

70
75

knurled collar 374 to accomplish this purpose.

After the diamond point 370 has been adjusted, then the rod 373 is locked in the block 372 by means of the locking clamp screw 383 so that there can be no relative movement between the rod and the block. A retaining plate 384 (Fig. 12) holds the block 372 from any upward movement as it is being rotated around on the T bar 371.

While the form of apparatus herein shown and described is admirably adapted to fulfill the objects primarily stated, it is to be understood that it is not intended to confine the invention to the forms of embodiment herein disclosed, for it is susceptible of embodiment in various forms all coming within the scope of the claims which follow.

What is claimed is:

1. In an apparatus for grinding an object in conformity with a master object, the combination of a spindle carrying said master object and the object to be ground; means for rotating said spindle and for simultaneously shifting the spindle along the axis on which it rotates; rotatable grinding means mounted on a non-shiftable support; a control device, mounted on a support shiftable to provide means for adjusting the relative positions of the grinding means and the control means, said control means cooperating with said master object as the latter is being rotated and laterally shifted past the control device, to control the position of the object to be ground relative to the periphery of the grinding wheel to cause the object to be ground to be an exact duplicate of the master object; and means to move the spindle toward the control device and the grinding means to constantly maintain the master object in contact with the control device and the object in contact with the grinding means.

2. In an apparatus for grinding an object in conformity with a master object, the combination of a spindle carrying said master object and the object to be ground; rotatable grinding means mounted on a fixed support; means for rotating said spindle and for simultaneously shifting the latter along the axis on which it rotates; means for also simultaneously shifting the spindle at right angles to the axis on which it rotates; a curved control device having the same contour as the rotatable grinding means for cooperating with the master object as the latter is being rotated and shifted in the said two directions to control the position of the object to be ground relative to the periphery of the grinding means to cause the object to be ground to be finished in exact duplicate as the master object; and means to rotate said control means on the axis of its curve to periodically present different sections of its periphery to the master object to maintain accuracy in the grinding of the object.

3. In an apparatus for grinding an object in conformity with a master object, the combination of a spindle carrying said master object and the object to be ground at a definite distance apart on said spindle; rotatable grinding means; means for rotating said spindle; a curved control device for cooperating with said master object; supporting means for said spindle, including a slide movable toward and away from the grinding means and the control device and a laterally movable member carrying said slide; and means for moving said member laterally in either direction while said spindle is being rotated to present all points of the surface of the

three-dimensional object to be ground to the grinding means, and to simultaneously present all points of the surface of the master object to the control device while the spindle is being rotated to control the grinding of the contour of said object to be ground.

4. In an apparatus for grinding an object in conformity with a master object, the combination of a spindle carrying said master object and the object to be ground at a definite distance apart on said spindle; rotatable grinding means; means for rotating said spindle; a curved control device for cooperating with said master object; supporting means for said spindle, including a slide movable toward and away from the grinding means and the control device and a laterally movable member carrying said slide; means for moving said member laterally in either direction while said spindle is being rotated to present all points of the surface of the three-dimensional object to be ground to the grinding means and to simultaneously present all points of the surface of the master object to the control device, while the spindle is being rotated to control the grinding of the contour of said object to be ground; an adjustable device for supporting said control device; and means to shift the adjustable device to maintain the distance between the control device and the grinding means the same as that between the master object and the object to be ground.

5. In an apparatus for grinding an object in conformity with a master object, the combination of a spindle carrying said master object and the object to be ground; rotatable grinding means; means for rotating said spindle and simultaneously shifting the latter along the axis on which it rotates; a control device for cooperating with said master object as the latter is being rotated and laterally shifted to control the position of the object to be ground relative to the periphery of the grinding means; and adjustable means for supporting said control device, including a rotatable device and means thereon for clamping said control device thereto for adjustment of the control device relative to the master object to present new surfaces of the control device to the master object.

6. In an apparatus for grinding an object in conformity with a master object, the combination of a spindle carrying said master object and the object to be ground; rotatable grinding means; means for rotating said spindle and simultaneously shifting the latter along the axis on which it rotates; a control device for cooperating with said master object as the latter is being rotated and laterally shifted to control the position of the object to be ground relative to the periphery of the grinding wheel; adjustable means for supporting said control device, including a rotatable device and means thereon for clamping said control device thereto for adjustment of the control device relative to the master object to present new surfaces of the control device to the master object; a plurality of radially arranged members each having a V-notch across the end thereof and into which the curved control device rests; means carried by the rotatable device for clamping said curved control device in the V notches of the radially arranged members; and a bearing means for the inner ends of the radially arranged members and against which said members are drawn by said clamping means to insure true concentricity of the working surface of said control device relative to the axis of the grinding means

to cause the object to be ground to be presented to the grinding means the same distance from the axis of the grinding means that the master object is from the axis of the supporting means of the control means.

7. In an apparatus for grinding an object in conformity with a master object, the combination of a spindle carrying said master object and the object to be ground; rotatable grinding means; means for rotating said spindle and simultaneously shifting the latter along the axis on which it rotates; a curved control device for cooperating with said master object as the latter is being rotated and laterally shifted to control the position of the object to be ground relative to the periphery of the grinding wheel; supporting means for said control device, including a plurality of rotatable disks, the axis of which coincides with the axis of the grinding means, and a plurality of radially arranged members each having a V notch cut across the end thereof to act as a bearing for said control device; clamping means supported by said disk for clamping said control device in said V notches of the radially arranged members; a cone-shaped bearing member against which the inner ends of the radially arranged members abut, the axis of said cone-shaped bearing member and the axis of the grinding means, and also the axis of the curved control device all coinciding; and means for shifting said cone-shaped bearing member along its axis to decrease the radius of the working surface of the control device to make it conform exactly to the radius of the grinding means, the radius of which changes due to constant wear and the dressing of the same.

8. In an apparatus for grinding an object in conformity with a master object, the combination of a spindle carrying said master object and the object to be ground at a definite distance apart from one another; rotatable grinding means; means for rotating said spindle and for simultaneously shifting the latter along the axis on which it rotates; a curved control rod for cooperating with said master object as the latter is being rotated and laterally shifted to control the position of the object to be ground relative to the periphery of the grinding means; adjustable supports for said control rod; means for clamping said control rod to the adjustable supports to retain the rod in position on its adjustable supports so that the radius of its working surface is the same as the radius of the grinding surface of the grinding means; and means for adjusting the supports for the control rod to change the radius of the working surface of said rod to make it conform to the radius of the grinding surface of said grinding means.

9. In an apparatus for grinding an object in conformity with a master object, the combination of a spindle carrying said master object and the object to be ground at a definite distance apart on said spindle; rotatable grinding means; an arcuate control device cooperating with said master object, the axis of said control device being the same as the axis of said grinding means, and the contour of said grinding means being exactly the same as the contour of said control device; a support for said control device; means for adjusting said support toward and away from said grinding means; means for adjusting said support toward and away from said grinding master object; means for rotating said spindle; a sliding support for said spindle for maintaining said master object in contact with said control device; and a traveling table carrying said sliding sup-

port and adapted to be moved at right angles to the movement of said sliding support to present all points of the surface of said master object to the control device while the spindle is being rotated to present all points of the object to be ground to the grinding means.

10. In an apparatus for grinding an object in conformity with a master object, the combination of a spindle carrying said master object and the object to be ground at a definite distance apart on said spindle; rotatable grinding means; means for rotating said spindle; a control rod cooperating with said master object, the shape of the periphery of the grinding means being exactly the same shape as the control rod; a plurality of members for supporting said control rod; means for clamping said rod to said members to shape said control rod so that its working surface is concentric to the axis of said grinding means; an adjustable conical support against which said supporting members are drawn by said clamping means; means for adjusting said conical support to change the radius of the working surface of said control rod; and means for supporting said spindle for movement toward and away from said control rod and the grinding means and also for movement laterally relative to said control device and the grinding means while the spindle is being rotated.

11. In an apparatus for grinding an object in conformity with a master object, the combination of a spindle carrying said master object and the object to be ground at a definite distance apart on said spindle; rotatable grinding means; means for rotating said spindle and simultaneously shifting said spindle along the axis on which it rotates; an adjustable control device for cooperating with said master object as the latter is being rotated and laterally shifted to control the position of the object to be ground relative to the periphery of the grinding wheel, said control device having an axis in axial alignment with the axis of the grinding means; and means for adjusting said control device radially relative to its axis.

12. In an apparatus for grinding an object in conformity with a master object, the combination of a spindle carrying said master object and the object to be ground at a definite distance apart on said spindle; rotatable grinding means; means for rotating said spindle and simultaneously shifting said spindle along the axis on which it rotates; an adjustable control device for cooperating with said master object as the latter is being rotated and laterally shifted to control the position of the object to be ground relative to the periphery of the grinding wheel, said control device having an axis in axial alignment with the axis of the grinding means; means for adjusting said control device radially relative to its axis; and means to adjust said control device transversely of its axis.

13. In an apparatus for grinding an object in conformity with a master object, the combination of a spindle carrying said master object and the object to be ground at a definite distance apart on said spindle; rotatable grinding means; means for rotating said spindle and simultaneously shifting said spindle along the axis on which it rotates; an adjustable control device for cooperating with said master object as the latter is being rotated and laterally shifted to control the position of the object to be ground relative to the periphery of the grinding wheel, said control device having an axis in axial alignment with

the axis of the grinding means; means for adjusting said control device radially relative to its axis, means to adjust said control device transversely of its axis; and means to adjust said control device horizontally along its axis.

14. In an apparatus for grinding an object in conformity with a master object, the combination of a spindle carrying said master object and the object to be ground at a definite distance apart on said spindle; rotatable grinding means; means for rotating said spindle and simultaneously shifting the latter along the axis on which it rotates; an adjustable control device for cooperating with said master object as the latter is being rotated and laterally shifted to control the position of the object to be ground relative to the periphery of the grinding wheel, said control device having an axis in axial alinement with said grinding means; and means to adjust said control device radially relative to its axis, transversely of its axis, and horizontally along its axis.

15. In an apparatus for grinding an object in conformity with a master object, the combination of a spindle carrying said master object and the object to be ground at a definite distance apart on said spindle; rotatable grinding means; means for rotating said spindle and simultaneously shifting the latter along the axis on which it rotates; an adjustable control device for cooperating with said master object to control the position of the object to be ground, said control device having an axis in axial alinement with the axis of the grinding means; and means to adjust said control device angularly around its axis.

16. In an apparatus for grinding an object in conformity with a master object, the combination of a spindle carrying said master object and the object to be ground at a definite distance apart on said spindle; rotatable grinding means; means for rotating said spindle and simultaneously shifting the latter along the axis on which it rotates; an adjustable control device to control the grinding of the object to be ground, the axis of the control device being in axial alinement with the axis of the grinding means; and means to adjust said control device radially relative to its axis and angularly around its axis.

17. In an apparatus for grinding an object in conformity with a master object, the combination of a spindle carrying said master object and the object to be ground at a definite distance apart on said spindle; rotatable grinding means; means for rotating said spindle and simultaneously shifting the latter along the axis on which it rotates; an adjustable control device for cooperating with said master object as the latter is being rotated and laterally shifted to control the position of the object to be ground

relative to the periphery of the grinding wheel, the axis of said adjustable control device being in axial alinement with the axis of said grinding means; and means to adjust said control device radially relative to its axis, angularly around its axis, transversely of its axis, and longitudinally along its axis.

18. In an apparatus for grinding an object in conformity with a master object, the combination of a spindle carrying said master object and the object to be ground at a definite distance apart on said spindle; rotatable grinding means; means for rotating said spindle and simultaneously shifting the latter along the axis on which it rotates; an adjustable control device for cooperating with said master object as the latter is being rotated and laterally shifted to control the position of the object to be ground relative to the periphery of the grinding means; adjustable means for supporting said control device, including a plurality of members extending radially from the axis of the working surface of said adjustable control device; and a cone-shaped member acting as a bearing for said radially arranged adjustable supporting members, the axis of the cone-shaped device coinciding with the axis of the working surface of said control device.

19. In an apparatus for grinding an object in conformity with a master object, the combination of a spindle carrying said master object and the object to be ground at a definite distance apart on said spindle; rotatable grinding means; means for rotating said spindle and simultaneously shifting the latter along the axis on which it rotates; an adjustable control device having a working surface for cooperating with said master object as the latter is being rotated and laterally shifted to control the position of the objects to be ground relative to the periphery of the grinding means; adjustable means for supporting said control device, including a plurality of members extending radially from the axis of the working surface of said adjustable control device; a cone-shaped member acting as a bearing for said radially arranged adjustable members, the axis of said cone-shaped device coinciding with the axis of the working surface of said control device; and means for adjusting said cone-shaped device longitudinally along its axis and relative to said members to change the radius of the working surface of said control device.
